(57) **CLAIM**

The ornamental design for an ear cover backing portion of a headphone device, as shown and described.

DESCRIPTION

FIG. 1 is a perspective view of an ear cover backing portion of a headphone device showing our new design.

FIG. 2 is a front profile view thereof.

FIG. 3 is a back profile view thereof.

FIG. 4 is a first side profile view thereof.

FIG. 5 is a second side profile view thereof.

FIG. 6 is a top plan view thereof; and,

FIG. 7 is a bottom plan view thereof.

The broken lines depict environment that forms no part of the claimed design.

1 Claim, 5 Drawing Sheets
